DEPT. OF THE UNITED STATES PATENT OFFICE

UNITED STATES PATENT OFFICE.

GUSTAVUS WIDEMAN, OF AURORA, ILLINOIS, ASSIGNOR TO THE RICHARDS MANUFACTURING COMPANY, OF AURORA, ILLINOIS.

DOOR-HANGER.

No. 845,989.

Specification of Letters Patent.

Patented March 5, 1907.

Application filed August 18, 1905. Serial No. 274,769.

To all whom it may concern:

Be it known that I, GUSTAVUS WIDEMAN, a citizen of the United States, residing at Aurora, in the county of Kane and State of Illinois, have invented certain new and useful Improvements in Door-Hangers, of which the following is a specification.

This invention relates to improvements in that type of door-hangers in which there is a hinged connection between the wheel-carrying frame and the door-connecting strap.

The improvements are in the construction of the door-strap and the means connecting the strap to the wheel-frame; and the especial objects attained are adjustability between the said parts, whereby the varying conditions met with in the application and use of such devices are provided for.

In the accompanying drawings, Figure 1 is a front elevation of a hanger constructed according to my invention. Fig. 2 is a side elevation of said hanger. Fig. 3 is a cross-section on the line 3 3 of Fig. 2. Fig. 4 is a cross-section on the line 4 4 of Fig. 1. Fig. 5 is a detail of the link which forms an important element of my invention. Fig. 6 is a detail in cross-section of the link, and Fig. 7 is an edge view of the wheel-hanger alone.

Referring to the details of the drawing, A represents a portion of a door to which my improved hanger is applied.

B represents the door-strap, which in this instance is a piece of sheet metal bent at right angles to form a horizontal flange b', which extends over the upper edge of the door and at a slight distance above the same. In the center of the strap-flange is a slot b², which is open at one end, and on each side of said slot are formed slots b³ b³, which are parallel with the slot b².

C represents the wheel-carrying frame which is preferably formed of sheet metal bent to form a housing for a grooved track-wheel c' mounted therein. The lower portion of the frame is bent to form a horizontal step c⁴ and a downwardly-extending terminal portion c². In each edge of the step a notch c³ is cut.

D represents the track, on which the wheel c' travels and which serves as a support for the hanger in the usual manner.

E represents a cast-iron bar formed with a flat face which lies next to and parallel with the inner face of the track D, thereby serving

as a track-guide and keeper for the hanger. At each end of the bar an ear e³ is formed and is provided with a hole e', which is adapted to receive the pintle f'. At the junction of the bar and each of the ears an inwardly-extending lug e² is formed, and said lugs fit the notches c³ in the edges of the wheel-carrying frame when the parts are assembled in operative position, and thus serve to hold the bar in a vertical position.

F represents a flat metal strap having each end bent up at right angles, and said bent-up portions are perforated to receive the ends of the pintle f', and the middle part has a hole in the center to receive a short screw-bolt G, which passes upwardly through the strap and through the slot b² in the flange b' of the strap B and is supplied with a nut which bears upon the upper side of the flange and serves to lock the strap upon the latter, as clearly shown in Figs. 3 and 4. As the slot b² is open at one end, the parts can be disconnected by loosening the nut on the bolt G and removing the pintle f'. As the width of the strap F is less than the length of the slots b³, a certain amount of lateral adjustment is possible in the relative positions of strap and flange b', as will be apparent from Fig. 4.

In a hanger constructed as described it will be apparent that the door-strap through its connection with the strap F will swing outwardly on the pintle f' as a pivot, while the bar E through its engagement with the notches c³ in the arm C will be held in a vertical position irrespective of the outward swing of the door. It will also be apparent that as the downwardly-bent end c² of the arm C terminates near the flange b' it will serve as a stop against the swinging of the door inwardly or in the direction opposite to that indicated by the dotted lines in Fig. 2.

What I claim is—

1. In a door-hanger, the combination of a wheel-carrying frame, a door-supporting strap, and means connecting said strap and frame, said means comprising two members hingedly connected, one of said members being rigidly connected with the door-strap, and the other member being detachably connected with the wheel-frame and constructed to form a track-guide.
2. In a door-hanger, the combination of a wheel-carrying frame, a door-supporting strap, and means connecting said strap and

frame, said means comprising two members hingedly connected, one of said members being detachably connected with the door-strap, and the other member being connected 5 with the wheel-frame, and constructed to form a track-guide.

3. In a door-hanger, the combination of a wheel - carrying frame, a door - supporting strap and means connecting said strap and 10 frame, said means comprising two members hingedly connected, one of said members being adjustably connected with the door-strap, and the other member being detachably connected with the wheel-frame and constructed 15 to form a track-guide.

4. In a door-hanger, the combination of a wheel - carrying frame, a door - supporting strap and means connecting said strap and frame, said means comprising a member detachably and adjustably mounted on the door-strap, a member detachably mounted 20 on the wheel-frame and constructed to form a track-guide, and means detachably connecting said members.

25 5. In a door-hanger, the combination of a wheel - carrying frame, a door - supporting strap and means connecting said frame and strap, said means comprising a member rigidly, adjustably and detachably connected 30 with the door-strap, and a member detachably connected with the wheel-frame and constructed to form a track-guide, and detachable means pivotally connecting said members together.

35 6. In a door-hanger, the combination of a wheel - carrying frame, a door - supporting strap, and means connecting said frame and strap, said means comprising a bent metal strap, detachably and adjustably mounted

on said door-strap, a bar detachably mounted 40 on the wheel-frame and constructed to form a track-guide, and a pin detachably connecting said bar with said bent strap.

7. In a door - hanger, a wheel - carrying frame, a door-supporting strap, and means 45 connecting said strap and frame, said means consisting of a strap detachably connected with the door-strap and having upwardly-bent ends, a bar arranged between the ends of said strap and having a flat face adapted to 50 lie parallel with the hanger-track, and a pin connecting said strap and bar.

8. In a door-hanger, a door-strap adapted to be secured to a door and having a horizontal portion adapted to overlie the top of a 55 door, said horizontal portion having slots formed therein, a strap detachably connected with said door-strap and adjustably fitting said slots, a wheel-carrying frame, and means pivotally connecting said frame with said 60 strap.

9. In a door-hanger, the combination of a wheel-carrying-frame having a horizontal foot with notches in its edges, a bar arranged 65 on said foot and having portions engaging said notches, said bar constructed to form a track-guide, a door-supporting strap having parallel slots, a metal strap having upturned ends pivotally connected with said bar, said strap adjustably arranged in said slots, and 70 means detachably connecting said metal strap with said door-strap.

In testimony whereof I affix my signature in presence of two witnesses.

GUSTAVUS WIDEMAN.
